UNITED STATES PATENT OFFICE.

HANS SORENSEN, OF SNOMA, SOUTH DAKOTA.

SPRINKLING ATTACHMENT FOR MOWERS.

SPECIFICATION forming part of Letters Patent No. 774,284, dated November 8, 1904.

Application filed July 1, 1904. Serial No. 214,911. (No model.)

To all whom it may concern:

Be it known that I, HANS SORENSEN, a citizen of the United States, residing at Snoma, in the county of Butte and State of South Dakota, have invented certain new and useful Improvements in Sprinkling Attachments for Mowers; and I do declare the following to be a full, clear, and exact description of the invention, such as will enable others skilled in the art to which it appertains to make and use the same.

My invention is an improved sprinkling attachment for mowing-machines and the like, its object being to provide improved means for keeping the cutting apparatus of such machines constantly moist, whereby the said apparatus is lubricated, the draft and friction materially reduced, and the cutting-teeth are prevented from gumming and clogging.

With these and other objects in view my invention consists in the construction, combination, and arrangement of devices herein-after described and claimed.

In the accompanying drawings, Figure 1 is a perspective view of a mowing-machine provided with my improved sprinkling apparatus. Fig. 2 is a detail perspective view, on a larger scale, of a portion of the cutting apparatus, showing the improved attachment thereon. Fig. 3 is a sectional view of the same, taken 30 on the plane indicated by the line *aa* of Fig. 2.

In the embodiment of my invention I provide a suitable water-reservoir vessel 1, adapted to be supported on the tongue or frame of the machine and provided with a faucet 2 and 35 with a clamp 10 to secure it in place. To the faucet is attached a flexible tube 3 of suitable length.

On the upper side of the finger-bar of the cutting apparatus, immediately in rear of the 40 cutter-bar, is a sprinkling-tube 4, which is triangular in form in cross-section with its apex on its front side and bearing directly against and in rear of the cutter-bar. The sprinkling-tube is provided with rearwardly-extending clamp-arms 5, of which a suitable number are employed, the said clamp-arms having their rear ends downturned, as at 6, to bear against the rear side of the finger-bar and secured thereto by means of set-screws 7. 45

50 The sprinkling-tube has that portion thereof

which coincides with the clip of the finger-bar offset vertically, as at 8, to clear the said clip. The said sprinkling-tube is further provided with a suitable number of discharge-tubes 9, one for each ledger-plate, which discharge-tubes are here shown as extending forwardly and as being curved in form and of such length as to be adapted to discharge directly onto the ledger-plates and onto the cutter-plates, as the latter move over the ledger-plates. The flexible tube is coupled to the sprinkling-tube, and it will be understood that when the faucet 2 is opened water will be fed from the reservoir or vessel 1 through the flexible tube, the sprinkling-tube, and the discharge-tubes and 60 directed upon the ledger-plates and cutter-plates, so as to prevent them from gumming and to constantly wash their surfaces. By reason of the triangular cross-sectional shape of the sprinkling-tube and the disposition of 65 its apex directly in rear of the cutter-bar grass is prevented from getting between the said sprinkling-tube and the said cutter-bar.

From the foregoing description, taken in connection with the accompanying drawings, 70 the construction and operation of the invention will be readily understood without requiring a more extended explanation.

Various changes in the form, proportion, and the minor details of construction may be 75 resorted to without departing from the principles or sacrificing any of the advantages of this invention.

Having thus fully described my invention, what I claim as new, and desire to secure by 80 Letters Patent, is—

1. In combination with cutting apparatus having a finger-bar, ledger-plates, a cutter-bar and cutter-plates, a sprinkling apparatus including a sprinkling-tube having means to 85 clamp it in place on the finger-bar and provided with discharge-tubes adapted to discharge water onto the ledger-plates and cutter-plates, substantially as described.

2. In combination with the finger-bar of a cutting apparatus, a sprinkling apparatus comprising a reservoir vessel, a flexible tube connected thereto, a sprinkling-tube connected to the flexible tube and provided with discharge-tubes and clamp-bars, the latter extending 90

rearwardly from the sprinkling-tube, engaging the rear and under sides of the finger-bar and being provided with set-screws to clamp them in place thereon, substantially as described.

3. In combination with a finger-bar and cutter-bar of a cutting apparatus, a sprinkling-tube bearing on the finger-bar and directly against the rear side of the cutter-bar and having its upper side inclined upwardly and

rearwardly from the cutter-bar, substantially as described.

In testimony whereof I have hereunto set my hand in presence of two subscribing witnesses.

HANS SORENSEN.
